US00D609332S

(12) **United States Design Patent**
Paterson et al.

(10) **Patent No.:** US D609,332 S
(45) **Date of Patent:** ** Feb. 2, 2010

(54) **BREAST PUMP BASE UNIT**

(75) Inventors: **Graeme L J Paterson**, Cheddar (GB);
Ralph J. Farrer, Keynsham (GB)

(73) Assignee: **Lansinoh Laboratories**, Alexandria, VA
(US)

(**) Term: **14 Years**

(21) Appl. No.: **29/314,951**

(22) Filed: **May 12, 2009**

(51) LOC (9) Cl. **24-02**

(52) U.S. Cl. **D24/109**

(58) **Field of Classification Search** D24/108-109,
D24/231; 604/73-76; D9/455, 517, 719,
D9/738-740, 744, 751

See application file for complete search history.

(57) **CLAIM**

The ornamental design for a breast pump base unit, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a perspective of the breast pump base unit;

FIG. 2 a front elevation of the breast pump base unit of FIG. 1;

FIG. 3 is a rear elevation of the breast pump base unit of FIG. 1;

FIG. 4 is a right side elevation of the breast pump base unit of FIG. 1;

FIG. 5 is a left side elevation of the breast pump base unit of FIG. 1; and,

FIG. 6 is a top plan view of the breast pump base unit of FIG. 1.

Preferably, base unit appears in Pantone 2705 or equivalent.

The broken lines are for environmental purposes only and form no part of the claimed design.
